UNITED STATES PATENT OFFICE:

WILLIAM ASHLEY WILSON AND GEORGE DUNCAN, OF LIVERPOOL, ENGLAND, AND GEORGE LAUDER, OF PITTSBURG, PENNSYLVANIA.

APPARATUS FOR SEPARATING AND FOLDING PAPER.

SPECIFICATION forming part of Letters Patent No. 276,369, dated April 24, 1883.

Application filed December 10, 1873. Patented in England November 19, 1870, No. 3,031.

To all whom it may concern:

Be it known that we, WILLIAM ASHLEY WILSON and GEORGE DUNCAN, both of Liverpool, England, and GEORGE LAUDER, of Pittsburg, in the State of Pennsylvania, have invented a certain new and useful apparatus for separating and folding paper as delivered from rotary web-printing machines, (said invention being substantially the same for which we obtained Letters Patent in England, granted to us November 19, 1870, and numbered 3,031;) and we do hereby declare that the following is a full, clear, and exact description of our invention, reference being had to the accompanying drawings, and to the letters or numbers of reference marked thereon.

Our invention consists mainly in the combination of three folding-rolls, one of said rolls provided with a folding-blade, one provided with a gripper, and one provided with both folding-blade and gripper, said rolls relatively arranged to give two consecutive folds to a sheet passing between the same; and, secondarily, in specific mechanism for delivering a sheet to the tri-roll folder, and for detaching the sheet from a perforated web, all as will hereinafter more fully appear.

To enable others skilled in the art with which it is most nearly connected to make and use our invention, we will proceed to describe its construction and operation.

In the accompanying drawings, which form part of our specification, Figure 1 is a side elevation of a rotary web-printing machine furnished with our improvements. Fig. 2 is a plan of the folding devices. Fig. 3 is a vertical section of the folding devices. Fig. 4 is a transverse section and elevation, showing the laying-fly. Fig. 5 is a transverse section of the folding-blade and slotted rolls, cams, and grippers, all of which parts are adapted to separate or detach sheets—say of newspaper size—from the web, to fold each such separated sheet three times, and to deliver the folded sheets.

In the accompanying drawings similar letters or numbers indicate the same parts.

The machinery or apparatus constituting the invention has been devised and perfected for the purposes of separating or detaching

sheets from the web as delivered from the printing-machine, folding such sheets as often as may be desired in practice, and delivering the folded papers. The end of the printed web is led direct to a saw or knife cylinder 55 and each sheet or length all but separated from the web. The web is then led between tapes to a pair of rollers, one having a folding blade or blades and the other a corresponding slot or slots on its periphery. These rollers run 60 faster than the saw or knife cylinder, and hence detach sheet after sheet. They also serve to give the first fold in consequence of each folding-blade delivering the "closed double edge" of a sheet. A brush is provided 65 to prevent the free end of the sheet, as aforesaid, from being carried round with the roller. To give the second fold, the sheets are passed between the upper and a third folding-blade and grooved rollers. For the third (usually a 70 cross) fold, the sheets are made to pass between cross-rollers. The fourth fold is effected by rollers whose axes are preferably parallel to the cross-rollers for the third fold. After receiving the fourth fold the papers slide down 75 on a fly, which delivers them.

In the accompanying drawings, 1 shows the web of paper as delivered to the rotating printing-cylinders. The course of said web before it is cut into sheets and of the sheets during 80 folding and laying is indicated on Fig. 3 by arrows. The web of paper, delivered at a uniform speed from the printing-cylinders, is guided between the pulleys 2 and rotating drum 3, thence between the said roll 3 and rotating 85 perforator-roll 4, carrying the toothed blade 5, whereby the web is transversely perforated at the required distances. The web so perforated passes downward and endward between the traveling tapes 6, driven by the roller 6^x, 90 thence upward with them and between the rollers 8, such rollers 8 being suspended by straps 9 from the eccentric pulley 10, fixed on the shaft 11. From rollers 8 the web passes between small rollers 12 to the folding-blade and 95 slot-rollers 13. When a sheet has traveled half-way through the rollers 13, the brush 14 causing the free single end to pass downward between the tapes 15, the protruding folding-blade 16^x in the lower roller 13 forces the sheet 100

into a slot in the upper roller 13, where it is held by grippers 16. The eccentric straps and pulleys are adjusted to cause the downward stroke of the rollers 8. After the closed double 5 of the sheet has been carried about half-way round the upper roller 13, and when the perforated line has passed the rollers 12, the sheet is torn off. The rollers 13 may be made to run faster than the tapes 6, and in this way tear 10 off sheet after sheet. To give the second fold, a protruding folding-blade, 16^x, on the top roller enters a slot in the roller 17, and grippers in 17 hold the sheet and deliver it past the rotating roller 18 to the tapes 19. The 15 folding-blades in the rollers 13 are caused to fall inward almost within the circumference thereof by the cams 20, for the purpose of allowing the paper to be easily carried away without objectionable friction. A large slot is formed 20 in the bottom roller 13, to allow the folding-blade on the top roller to pass. Cams 21 operate the grippers 16. The tapes 19 convey the sheets, after two folds are made, downward over the rotating cross-roller 22, where a knife, 25 23, caused to vibrate by slotted lever 24, connecting-rods 25, centered lever 26, cam 27, and return-spring 28, gives the third fold by forcing the sheet between the said cross-rollers 22, from which it is carried downward by the 30 tapes 29. The tapes 29 are carried on the laying-fly, which is caused to vibrate by the connecting-rod 30, operated through the eccentric-pin 31.

It will be evident that, as shown on the 35 drawings, all the parts in direct contact with the web, as well as with the separated and folded sheets of paper, have the same surface speed, and that the laying-fly delivers a folded sheet during each double vibration.

40 It will also be evident that the moving parts are so geared that every revolution of the driving-shaft causes one revolution of the perforator-roll 4, and also one revolution of the pin 31.

45 Having now described the nature of our

50 said invention and particularized the same by details which after lengthened trials we have found to answer well in practice, we would have it understood that we do not claim broadly rotary folding mechanism, either alone or in combination with web-printing mechanism, web-severing mechanism, or sheet-controlling mechanism. Neither do we claim a folding-blade mounted in a revolving carrier, in combination with a companion carrier provided with devices which seize, retain, and carry the doubled sheet, whether such combination be used alone or in conjunction with mechanism for severing a web and mechanism for controlling the leading end of a sheet. Neither do we herein claim broadly the combination of a rotary cylinder or carrier provided with a folding-blade, a rotary cylinder or carrier provided with sheet-nipping devices and a folding-blade, and sheet-seizing devices which co-operate with the last-named folding-blade to impart a second fold to the sheet, except when said sheet-seizing device is a roll provided with a gripper; but 55 60 65 70

What we do claim is—

1. The combination of three folding-rolls, one of which is provided with a folding-blade and a gripper, a second with a folding-blade, and a third with a gripper, substantially as and for the purpose specified.
2. In combination with folding-cylinders 13, rollers 12, and tapes 6, the rollers 8, suspended from an eccentric pulley by suitable straps, so as to receive a downward motion at stated times to separate the sheets of paper, substantially as specified.

75 WILLIAM ASHLEY WILSON.

GEORGE DUNCAN.

GEORGE LAUDER.
